UNITED STATES PATENT OFFICE.

ALFRED DAY, OF PHILADELPHIA, PENNSYLVANIA.

DESIGN FOR A CHECKER-BOARD.

55,455.

Specification for Design.

Patented June 15, 1920.

Application filed March 17, 1920. Serial No. 366,708. Term of patent 14 years.

To all whom it may concern:

Be it known that I, ALFRED DAY, a citizen of the United States, residing in the city and county of Philadelphia, State of Pennsylvania, have invented a new, original, and ornamental Design for Checker-Boards, of which the following is a specification, reference being had to the accompanying drawing, forming part thereof.

The figure is a plan view of a checker board showing my new design.

I claim:

The ornamental design for a checker board as shown.

ALFRED DAY.
